UNITED STATES PATENT OFFICE.

JOHN J. SULLIVAN, OF CHICAGO, ILLINOIS.

AUTOMOBILE STREET-SPRINKLER.

No. 806,378.

Specification of Letters Patent.

Patented Dec. 5, 1905.

Application filed April 27, 1905. Serial No. 257,718.

To all whom it may concern:

Be it known that I, JOHN J. SULLIVAN, a citizen of the United States, and a resident of Chicago, in the county of Cook and State of Illinois, have invented certain new and useful Improvements in Automobile Street-Sprinklers, of which the following is a full, clear, and exact description.

Heretofore the sprinkling-carts employed in the congested districts particularly of large cities were drawn by horses and considering the size of the tanks were unwieldy and an obstruction to the traffic in the streets.

The object of my invention is to make a dirigible automobile sprinkling-wagon which can have greater water-carrying capacity and can be more easily controlled than heretofore, while occupying less space than the old-style cart and draft-animals attached thereto; and a further object is to utilize the propelling power to forcibly expel and spray the water. This I accomplish by the means hereinafter fully described and as particularly pointed out in the claims.

In the drawings, Figure 1 is a side elevation of my invention. Fig. 2 is a rear end elevation thereof. Fig. 3 is a front end elevation. Fig. 4 is a plan view of my improved sprinkler with the tank removed. Fig. 5 is a detail view showing one of the cross-frames with its ends attached to the side sills, which latter are in section. Fig. 6 is a perspective view of the sprinkling mechanism removed from the remainder of the wagon.

In the drawings, A A represent the I-beam sidesills, and B B the I-beam end sills, of a rectangular body-frame, in which the horizontally-disposed cylindrical tank C is seated and secured by means of stout metal bands *a a*. These metal bands are provided with V-shaped offsets *b b* just above the plane of the body-frame, which rest upon the side sills, which latter near their ends are provided with depending pedestals *c c*, in which the cushioned journal-boxes of the rear drive-axle D and the forward cushioned steering-axle E are seated. The forward axle, similar to the steering-axle of automobiles, does not revolve, and its ends are forked, and between the ends of the branches of these forks bosses *d*, whose axes are vertical, are pivoted. The bosses are provided with horizontal bearing studs or spindles for the boxes of the supporting-wheels *e e* and with forwardly-projecting arms *f f*, which are connected by the links *g g* to the extremity of an arm *h* on the

lower end of the vertical steering-shaft F. Shaft F is journaled in suitable bearings secured to the forward end sill of the body-frame, and the foot-rest G secured to the adjacent end of the tank, and its upper end is provided with a hand-wheel, which is conveniently located in front of the chauffeur's seat H. This seat could be made of any suitable construction and secured to the front end of the tank. I prefer, however, to cut away the upper segment of the tank at the end and recess a portion of the head and to build the seat in this cut-away portion, substantially as shown in the drawings. The portion of the tank X immediately below the seat H is partitioned off from the balance of the tank to form a gasoline-storage compartment, which is always cool and is suitably connected to the power-generating apparatus by the pipe *x*.

The power-generating apparatus I of my invention I prefer to suspend below the tank by means of a suitable cross-frame or bolster J, which is preferably truss-shaped, substantially as shown in Fig. 5 of the drawings, and has its ends riveted or otherwise secured to the webs of the side sills of the body-frame. The actuating movement of the power-generating apparatus is transmitted, preferably by a piston-rod A', to the transmission-gear housed in a suitable casing K, arranged under the tank in alignment with the power-generating apparatus and supported by means of cross-frames J' J', constructed and arranged similar to cross-frame J. The transmission-gear actuates the transverse drive-shaft M, which is shown as being journaled in the rear end of the casing and in suitable bearings secured to and depending from the side sills of the body-frame. The ends of this drive-shaft extend through their bearings and are provided with small sprockets *h' h'*, which are connected, by means of an endless chain *q*, to sprockets P, of considerably greater diameter, mounted on the drive-axle D between the journals thereof and the wheels on the ends of said axle. The drive-axle is provided with two diametrically oppositely extending cranks *g' g'*, and the motion of these cranks is imparted to pistons *k k* in the pump-cylinders *n n* by means of pitmen N N. The pump-cylinders just referred to each communicate with one of the transverse horizontal legs O O of the vertical discharge-pipe R of the tank, and the ends of these branches or legs are bent rearwardly and are connected to and commu-

nicate with a segment-shaped tubular sprinkler S, preferably of the design shown in the drawings. The discharge-pipe is provided with a suitable valve T, the axis of which is 5 horizontal, and has one end extending beyond the case and provided with a transverse arm which is connected by a suitable cable or chain r through suitable guiding devices to the driver's seat, where it is connected to a suitable 10 pivoted lever s, one arm of which is elongated to provide a suitable handle, by manipulating which the driver can open and close the discharge of the water from the sprinkler according as desired.

15 What I claim as new is—

1. In a street-sprinkler, the combination with a horizontally-disposed cylindrical tank, a body-frame consisting of side sills and end sills formed of I-beams and bolsters mediate 20 said end sills formed of drop-frame truss-shape construction, and endless bands surrounding said tank and having offsets that rest upon said side sills, of power-generating apparatus and transmission-gear actuated 25 thereby both of which are supported by said bolsters, a drive-axle driven by said gear, sprinkling devices connected with said tank, and means which while said sprinkler is in motion force the water out of said sprinkler 30 under pressure.

2. In a street-sprinkler, the combination with a horizontally-disposed cylindrical tank, a body-frame consisting of side sills and end sills formed of I-beams and bolsters mediate 35 said end sills formed of drop-frame truss-shape construction, and endless bands surrounding said tank and having offsets that rest upon said side sills, of power-generating apparatus and transmission-gear actuated thereby both 40 of which are supported by said bolsters, a drive-axle driven by said gear, sprinkling devices having valve-controlled connection with said tank, and means which while said sprinkler is in motion force the water out of said 45 sprinkler under pressure.

3. In a street-sprinkler, the combination with a horizontally-disposed cylindrical tank having a seat made within the circumference thereof at one end, and a rectangular body-frame having end sills and side sills formed 50 of I-beams and bolsters mediate said end sills formed of drop-frame truss-shape construction within which said tank is seated and bands encircling said tank provided with off- 55 sets that rest upon the side of said body-frame, of suitable running-gear attached to said body-

frame, and valve-controlled sprinkling devices directly operated by said running-gear connected and communicating with said tank.

4. In a street-sprinkler, the combination 60 with a horizontally-disposed cylindrical water-tank having a portion thereof partitioned off for gasoline-storage chamber, and a rectangular body-frame having end sills and side sills formed of I-beams and bolsters mediate 65 said end sills formed of drop-frame truss-shape construction within which said tank is seated and bands encircling said tank provided with offsets that rest upon the side of said body-frame, of suitable power-generating 70 apparatus having suitable connection with said gasoline-chamber, running-gear attached to said body-frame and driven by said power-generating apparatus, and a pump connected with said tank and directly operated by said 75 running-gear.

5. In a street-sprinkler, the combination with a horizontally-disposed cylindrical water-tank having a portion thereof partitioned off for a gasoline-storage chamber, and having 80 a seat made within the circumference of said tank above said chamber, and a rectangular body-frame having end sills and side sills formed of I-beams and bolsters mediate said end sills formed of drop-frame truss-shape 85 construction within which said tank is seated, of suitable power-generating apparatus having suitable connection with said gasoline-chamber, running-gear attached to said body-frame and driven by said power-generating 90 apparatus, and a pump connected with said tank and directly operated by said running-gear.

6. In a street-sprinkler, the combination with a horizontally-disposed cylindrical water-tank, a rectangular body-frame having end sills and side sills formed of I-beams and bolsters mediate said end sills formed of drop-frame truss-shape construction, power-generating apparatus, running-gear driven thereby, valve-controlled sprinkling devices connected to and communicating with said tank, and a pump directly actuated by said running-gear and connected with said sprinkling devices from which they forcibly expel the 100 water.

In testimony whereof I have hereunto set my hand this 21st day of April, A. D. 1905.

JOHN J. SULLIVAN.
